UNITED STATES PATENT OFFICE.

ROBERT DEMPSTER, OF MARIETTA, OHIO, ASSIGNOR TO MARY DEMPSTER, HENRY H. BURNS, AND NORMAN MORROW, OF MARIETTA, OHIO.

APPARATUS FOR MAKING OIL-GAS.

SPECIFICATION forming part of Letters Patent No. 703,901, dated July 1, 1902.

Application filed November 5, 1901. Serial No. 81,248. (No model.)

To all whom it may concern:

Be it known that I, ROBERT DEMPSTER, a citizen of the United States, residing at Marietta, in the county of Washington and State of Ohio, have invented a new and useful Apparatus for Vaporizing Liquids, of which the following is a specification.

My invention relates to certain improvements in apparatus for vaporizing liquids, and is intended principally for the formation of a fixed gas from liquid hydrocarbons of any character.

One object of the invention is to provide a retort-vaporizer having or containing a lining or packing of asbestos, which is saturated with oil or oily vapor, the particles of hydrocarbon being broken up in order that they may more thoroughly and effectually be operated upon by the heat.

A further object of the invention is to so construct the device as to prevent the escape of any of the hydrocarbon in liquid form into the main retort, which is subjected to the direct action of the heat, the tarry matter and carbonaceous residuum being retained within a primary vaporizing-chamber having an outlet through which it may be readily removed as from time to time may become necessary.

A still further object of the invention is to prevent the manufactured gas from carrying off any uncombined carbon, this being effected by straining or filtering the gas through asbestos or similar fibrous material before it reaches the escape-pipe.

With these and other objects in view the invention consists in the novel construction and arrangement of parts hereinafter more particularly described, illustrated in the accompanying drawings, and particularly pointed out in the appended claims.

In the drawings, Figure 1 is a longitudinal sectional elevation of a vaporizing apparatus constructed in accordance with my invention.

Fig. 2 is a transverse sectional elevation of the same on the line 2 2, Fig. 1. Fig. 3 is a vertical sectional elevation of one of the retorts drawn to an enlarged scale. Fig. 4 is a sectional plan view of a portion of the superheater on the line 4 4 of Fig. 1. Fig. 5 is

an enlarged sectional elevation of the gas-escape pipe leading from the superheater.

Similar numerals of reference are employed to designate corresponding parts throughout the several figures of the drawings.

10 designates a cast-iron retort of rectangular form in cross-section and provided at each of its ends with upwardly-extending gas-outlets 11, through which the gas escapes to an upper superheating-chamber 12. The 60 number of retorts 10 employed depends entirely on the capacity of the apparatus. In the present instance I have shown five retorts extending parallel with each other, a space being left between each of the retorts 65 for the passage of the products of combustion arising from a mass of fuel to be supported by a lower grate 13.

The ends of the retort are provided with removable covers 14, having inner flanges 15, 70 acting partially as guides and partly to hold the covers in position. The covers are firmly clamped in place by longitudinal bolts 16, extending from end to end of the retort and having securing-nuts 17 at one or both ends to 75 bind the doors firmly in place. The covers or doors may be provided with packing at their edges or may be luted in the usual manner. On the inner side of each cover 14 is an annular rib 18, forming a support or socket 80 for the reception of the end of a pipe 19, said pipe being of such length as to be firmly clamped when the bolts 16 are tightened. The pipe 19 is provided on its upper side with a series of perforations 20, extending throughout the entire length of said pipe. An oil-supply pipe 21 is arranged at the front of the vaporizer, and to said pipe is connected a series of smaller pipes 22, each being tapped into a recess or opening in the retort-covers 90 immediately in line with the pipe 19. Each pipe 22 is provided with a separate needle-valve 23, by which the flow of oil may be governed, or in case of the clogging of the pipe or of the pipe 19 by the accumulation of the 95 heavier hydrocarbons the needle-valve of said pipe may be temporarily closed without interfering with the manufacture of gas in the remaining retorts. On the inner side of the door or cover within the pipe 19 is a short 100

pipe-section 22' in alinement with the pipe 22 and provided at its inner end with a cap or cover 23', having a minute orifice or opening through which the liquid hydrocarbon passes into the tube 19. At the rear cover of each retort is a valved pipe 24 in alinement with the pipe 19 and so arranged as to permit of the withdrawal of tar and such other heavy hydrocarbons as may accumulate in said pipe 19.

Surrounding the pipe 19 is a perforated pipe 19' of such diameter as to leave an annular interspace, in which I place a quantity of loose asbestos fiber, the ends of said pipes being supported on the outer edge or rim of the annular rib 18, and as a further support and to prevent any escape of gas through the ends of the pipe I employ metallic packing-rings 20' between said pipes 19 and 19'.

20 Supported on the bottom of the retort and extending over the pipe 19' is a shield or cover 25, formed of wire-gauze or foraminated sheet metal, the gauze or metal being arched, as shown more clearly in the drawings.

25 Supported by the arched gauze 25 is a second sheet of gauze 26, bent into substantially semicircular form in cross-section and so arranged as to form at the top of the retort a gas-passage to permit of the escape of the gas from the retort to the vertical passages 11 at the opposite ends thereof. The space enclosed by the gauze 25 and the spaces formed between the gauze sections 25 and 26 are filled with asbestos, the asbestos being first 30 prepared by loosening its fibers and then packing the fibers very loosely within such spaces. The sheets of gauze serve to hold the asbestos fiber in place, and the upper sheet of gauze is so arranged as to at all times preserve an 35 open and free passage for the gas to the opposite ends of the retort.

The superheater 12 acts as a crown-sheet for the furnace and at each of its ends is provided with a series of downwardly-projecting neck portions 25', adapted to enter the vertical passages 11, extending upwardly from the opposite ends of the retorts to the superheater. The opposite sides of the superheater are provided with a series of vertical passages 27, 40 forming flues for the passage of the products of combustion, the burning gases arising from the mass of fuel passing between and around all of the retorts and after striking the lower face of the superheater passing through the side passages 27 and finally escaping through 45 an outlet-flue 27'.

The retorts are firmly secured at each end to the vaporizer by U-shaped bolts 28, the lower central portions of which pass under 50 cross-bars 29 in the vertical passages of the retort, the upper portions of said bolts extending through the top of the superheater and being provided with suitable nuts 30.

The arrangement of the flues or passages 55 27 divides the sides of the superheater into a series of rectangular chambers 31, the outer ends of which are closed by removable cover-

plates 32, held in position by bolts 33, extending transversely through the superheater and passing through alining cover-plates 32 at opposite sides of said superheater. The removal of these doors permits of the cleaning of the superheater should there be any accumulations of carbonaceous matter.

In the uptakes 11, leading from the opposite ends of the retort, are placed wire screens 32', between which is placed a quantity of loose asbestos fiber 33', through which the escaping gas is filtered in order to prevent the escape of any free carbon.

80 In the superheater is arranged a gas-outlet pipe 34, perforated at suitable intervals and coupled at one end to a pipe 34', which may lead to a suitable gasometer or, if desired, to a washer or purifier, although I have found 85 in practice that the gas as it escapes from the superheater is fixed gas of high illuminating power and containing little or no free carbon.

In order to more thoroughly filter and purify the gas, the outlet-pipe 34 is surrounded 90 by a perforated pipe 35, and between said pipes 34 and 35 is placed a filling of loose asbestos fiber, which further strains and filters the escaping gas.

The various retorts and the superheater being bolted together form a rigid structure 95 which is held in position within a furnace-casing constructed in any desired manner, but preferably formed of a number of independent sections which may be readily taken 100 apart when the apparatus is to be shipped, said sections being of such character as to dispense with the employment of the usual fire-brick.

The preferred form of casing is made of 105 four main sections comprising end walls 36 and 37 and side walls 38 and 39, shaped to conform to the general outline of the furnace, and each end wall having an ash-pit door 40, the feed-door 41, and a door 42, which may 110 be opened to gain access to the ends of the retort. This latter door is preferably made in sections, owing to the arrangement of the pipes 22 and 24. Each section of the casing is provided with a large number of openings 115 44, countersunk on the inner side to prevent ashes lodging in the hole, and over all of the casing extends a sheet-iron casing 45, separated from the sections 36, 37, 38, and 39 by a continuous air-space to prevent to a considerable extent the heating of such outer casing.

In the operation of the device liquid hydrocarbon is fed from any suitable support of supply through pipe 21 and each of the pipes 125 22 through the perforated pipes 19 in the interior of the retorts 10, the oil being forced in a minute stream through the perforations in the caps 23'. Fuel having been applied to the grate-bars 13 and the retorts heated to a 130 greater or less degree, the radiated heat will vaporize the oil contained within the preliminary vaporizing chambers or retorts 19, forming a heavy vapor containing all of the

lighter hydrocarbons and some of the heavy hydrocarbons, said vapor passing out through the asbestos contained in the space between the pipes 19 and 19' and escaping through the 5 perforations in the latter pipe to the retort 10. The heavy vapor will be broken up by the fibrous asbestos and being minutely and more intimately in contact with a heated surface will be rapidly and thoroughly gasified 10 and finally escape through the outlet 11 into the superheater 12. The asbestos is highly heated and owing to its fibrous nature forms a very extensive surface for contact with the heavy vapor, insuring the rapid formation of 15 a practically fixed gas. Should the gas retain any free carbon, the asbestos strainer or filter in the uptakes 11 will purify it before its entrance to the superheater 12. Owing to the greater heat in the superheater the gas 20 will become permanently fixed, and should it still retain any free carbon such carbon will be removed during the final passage of the gas through the filtering medium formed by the asbestos contained between the pipes 25 35 and 34.

The device is of such character that it may readily be taken apart for cleaning, and the arrangement of the primary vaporizing-tube 19 is such that the larger proportion of the 30 heavier hydrocarbon will remain in such tube, from whence they may be withdrawn through the discharge-pipe 24.

The structure may be modified in a variety of ways, and its proportions may be altered 35 to increase or decrease the quantity of gas manufactured, and the minor details of construction may be altered to accommodate various requirements of use without departing from the spirit or sacrificing any of the advantages of my invention.

Having thus described my invention, what I claim is—

1. In a device of the class specified, a retort, means for heating the same, a perforated 45 pipe centrally disposed within said retort and forming a primary vaporizing-chamber, an oil-feeding device situated at one end of said pipe, and a second perforated pipe surrounding said primary vaporizing-chamber.

50 2. In a device of the class specified, a retort, means for heating the same, two concentrically-arranged perforated pipes arranged within said retort, and devices for supplying a liquid hydrocarbon to the inner of said 55 pipes, substantially as specified.

3. In a device of the class specified, a retort, means for heating the same, two concentrically-arranged and perforated pipes located within said retort, means for supplying liquid 60 hydrocarbon to the inner pipe, and a packing or filling of asbestos fiber arranged in the space between said pipes.

4. In a device of the class specified, a retort, a filling of asbestos fiber arranged within 65 the retort, means for heating the retort, two concentrically-disposed pipes arranged within

said retort and perforated for the passage of oily vapor, and means for supplying liquid hydrocarbon to the inner of said pipes.

5. In a device of the class specified, a retort having an asbestos filling, a reticulated shield or guard for confining said filling in place, a perforated primary vaporizing-chamber located within said retort, means for supplying liquid hydrocarbon to said primary 70 vaporizing-chamber, and means for heating the retort.

6. In a device of the class specified, a retort having a filling of asbestos fiber, reticulated screens arranged within the retort and 80 adapted to hold the fiber in position and to form a free gas-passage, a perforated primary vaporizing-chamber located within said retort, means for supplying liquid hydrocarbon to said primary vaporizing-chamber, and 85 means for heating said retort.

7. In a device of the class specified, a retort having a filling of asbestos fiber, two concentrically-disposed and perforated tubes arranged centrally within the retort, the 90 space between said tubes being filled with asbestos fiber, means for supplying liquid hydrocarbon to the inner of said tubes, and means for heating said retort.

8. In a device of the class specified, a retort having a filling of asbestos fiber, reticulated screens for confining said fiber in position, two concentrically-disposed perforated tubes arranged centrally within the retort, the space between said tubes being filled with 100 asbestos fiber, means for supplying liquid hydrocarbon to the inner of said tubes, and means for heating said retort.

9. In a device of the class specified, a retort, means for heating the same, a perforated 105 tube arranged centrally within said retort and forming a primary vaporizing-chamber, and an oil-feed tube extending partly within said perforated tube and having a reduced-end discharge-opening.

10. In a device of the class specified, the combination with a retort, of a superheater arranged above and connected with the retort, and a filtering-screen formed of asbestos fiber arranged in the passage between the 115 retort and the superheater.

11. In an oil-gas apparatus, a retort, a primary vaporizing-chamber arranged within the same, a superheater disposed above and connected with the retort, reticulated screens 120 arranged in the passage between the retort and the superheater, and a filtering-bed, formed of asbestos fiber, arranged between said reticulated screens, substantially as specified.

12. In a gas apparatus, a superheater, a perforated escape-pipe arranged therein, a second perforated pipe arranged around the escape-pipe, and an asbestos filling disposed in the space between said pipes, substantially 130 as specified.

13. In a device of the class specified, a su-

perheater, two concentrically-disposed and
perforated pipes arranged within said heater,
an asbestos fiber forming a packing or filling
in the space between said pipes, and a gas-
5 escape pipe connected to the inner of said
concentric pipes.

In testimony that I claim the foregoing as

my own I have hereto affixed my signature in
the presence of two witnesses.

ROBERT DEMPSTER.
